UNITED STATES PATENT OFFICE.

LOUIS LUMIÈRE, OF LYON, FRANCE.

LOUD-SPEAKING APPARATUS OF THE ELECTROMAGNETIC TYPE.

Application filed May 26, 1923, Serial No. 642,918, and in France January 11, 1923.

In my French Patent No. 401,501 of the 25th July 1908, I described an acoustic diaphragm composed of a folded sheet with warped elements which may be made of any suitable material such as pasteboard, paper or the like and connected together.

The present invention relates to the use of the diaphragm for producing intense acoustic waves, the electro-magnetic vibrations being converted into acoustic vibrations of large amplitude.

My invention consists essentially in the combination of the diaphragm with an electro-magnetic receiver in such manner that the vibrations of the electro-magnetic element shall be transmitted to the said diaphragm and shall be converted by the latter into acoustic waves, the whole being so combined that the diaphragm or cell shall be acted upon at the most suitable part of the same.

The electro-magnetic receiver may consist of an electro-magnet provided with an armature of the ironclad type, such as a telephone receiver whereof the disc, strip or like vibrating member is connected with the said diaphragm or cell. By reason of the very thin construction of the metallic disc of the telephone it is preferable to provide a great number of contact surfaces between the said disc and the element transmitting its vibrations to the diaphragm, and these contacts may be disposed according to a line or to a set of points having preferably an equal spacing.

The following description and appended drawings which are given by way of example set forth the said invention.

Fig. 1 is a vertical section of a telephone receiver of the Brown type as used in telegraphy or radio-telephony, combined with the diaphragm having warped elements.

Fig. 2 is a like section of an ordinary telephone receiver combined with the diaphragm having warped elements.

Fig. 3 is a transverse section shewing various telephone receivers or electro-magnets with vibrating strips or discs acting upon a single diaphragm with warped elements, and at several points on the same.

Fig. 4 is a plan view of Fig. 3.

Figs. 5 and 6 are detail views of a joint without play which connects the diaphragm with the vibrating electro-magnetic element.

Figs. 7 and 8 relate to another modification.

In the form of construction shewn in Fig. 1, the vibrating strip *a* of the telephone receiver of the Brown type, in which the vibrations are produced by magnetic attraction due to vibratory currents passing in the coils *b* of the electro-magnet, will produce in the diaphragm with warped elements *c* a vibratory motion which is converted into acoustic vibrations. This transmission takes place through the intermediary of a light metal point or rod which is secured to the acoustic diaphragm and bears upon the strip *a* or is attached thereto by a joint without play which will be further described. The operating point is suitably chosen and may also be made adjustable by providing at the lower part a suitable mounting for the telephone receiver whereby the combination of strip and electro-magnet can be moved relatively to the said diaphragm.

The diaphragm is held between two rigid washers *R*, Fig. 4, and is supported by various struts *g*, for instance three in number, secured at one end to the telephone casting *f* and at the other to the said washers by screws or bolts *i*.

In the constructional form shewn in Fig. 2, the diaphragm is caused to bear upon the vibrating plate *e* of an ordinary telephone receiver at a point which has an eccentric position relative to the said plate in the example represented. In other cases, the operating point *k* might be varied by moving the electro-magnet element within the box by suitable regulating means.

In the form of construction shewn in Fig. 3, the said diaphragm is acted upon at various points which are equidistant from the centre of the diaphragm, four for example, and at a certain distance from the centre. To this end the diaphragm may be provided with various rods *d* suitably disposed and attached to the same, and caused to bear upon the vibrating strips or plates *l*, so that a plurality of electro-magnetic elements will concur in the vibration of the said diaphragm.

In the arrangements in which the rods *d* may as above stated be attached to the strip *a* by a joint without play, the joint is preferably made as shewn in Figs. 5 and 6 by means of a fork *d*¹ in which is engaged a ball *d*² slightly engaging in a small hole in each branch of the fork, so that the said fork will hold the ball while allowing it to turn about without play; to the said ball is

soldered or otherwise secured the end of a rod k^1 whose other end is attached to the diaphragm c by any suitable means, the end of the forked member d^1 being soldered to the vibrating element consisting of the strips or plates a, e, l .

In the arrangement which is shewn by way of example in transverse section and on a small scale in Fig. 7, and whereof Fig. 10 8 shews the details of the central part on a larger scale, the vibrations are transmitted from the membrane e of the telephone through the medium of a very light tube m which is secured by adhesion or by like 15 means to the diaphragm c ; it should be given a considerable diameter and is caused to bear upon the telephone disc or membrane e .

The said tube may be composed of a paper 20 strip wound up in several turns while coated with adhesive substance, and the whole varnished; the upper end of the tube is slotted and overturned within and without so as to form various lugs m^1 which are caused 25 to adhere to the diaphragm c through the medium of one or more washers n preliminarily secured to the diaphragm. The bottom of the tube bears upon the said disc e of the telephone or of the acoustic cell 30 (in coaxial position) and if necessary through the intermediary of a washer q , Fig. 8, made of compressed felt, cork or the like, the pressure being adjusted by suitable 35 means. The lower edge of the said tube r may have a toothed form, Fig. 8, so as to constitute a series of uniformly spaced contact portions for transmitting the vibrations from the telephone disc to the said diaphragm.

40 Obviously, the said constructional forms

are given solely by way of example, and the said invention may be carried into effect by the use of embodiments of a widely varying nature.

What I claim is:—

1. An electro-magnetic loud speaker for the production of intense acoustic waves by converting electro-magnetic vibrations into acoustic vibrations of large amplitude comprising in combination a diaphragm having warped members in the manner of a circular fan, an electro-magnetic receiver constituted by a vibrating blade situated in front of conveniently disposed electromagnets, and a pointed rod fixed to the diaphragm at a convenient point and resting upon the vibrating plate.

2. An electro-magnetic loud speaker for the production of intense acoustic waves by converting electro-magnetic vibrations into acoustic vibrations of large amplitude comprising in combination a diaphragm having warped members in the manner of a circular fan, an electro-magnetic receiver constituted by a vibrating blade situated in front of conveniently disposed electromagnets, a rod for connecting a convenient point of the vibrating plate to a convenient point of the diaphragm for transmitting the vibrations from one to the other, and means for displacing the whole of the electro-magnetic receiver and of the vibrating blade relatively to the diaphragm to have the pointed rod resting upon the most convenient point of the vibrating blade.

In testimony that I claim the foregoing as my invention I have signed my name hereto.

LOUIS LUMIERE.
